MULTIPLE FUEL BURNER SYSTEM

Ralph J. Plein, Chicago, Ill., assignor to Drying Systems, Inc., Chicago, Ill., a corporation of Illinois

Application August 8, 1938, Serial No. 223,658

9 Claims. (Cl. 158—28)

The invention relates generally to fuel burners and more particularly it relates to fuel burning systems having a plurality of individual fuel burners.

5 The primary object of the present invention is to provide a multiple burner starting and control system which is simple and economical in construction and operation.

Another object is to provide a multiple burner starting and control system having an electric ignition means for all of the individual burners wherein the customary duplication of equipment for each burner unit is rendered unnecessary.

More specifically, it is an object of the present 15 invention to provide such a multiple burner system wherein a single ignition transformer of relatively small size serves to supply high voltage ignition current for all of the individual burners without overload upon the single transformer.

20 Another object is to provide a new and improved multiple burner system wherein a single safety control system governs a relatively large number of main burner units.

A further object is to provide a multiple burner 25 system wherein a single control system acts through a plurality of parallel main burner control circuits to effect control of a plurality of main burner units.

Other objects and advantages will become apparent from the following description, taken in connection with the accompanying drawings, in which:

Fig. 1 is a wiring diagram illustrating a multiple burner system embodying the features of the 35 invention.

Fig. 2 is a view of the distributor device and its drive motor, the distributor device being shown in central section.

Fig. 3 is a sectional view of the distributor device taken along the line 3—3 of Fig. 2.

40 In the form chosen for disclosure herein the invention is embodied in a multiple burner system adapted for supplying heat to the various units of an industrial baking or drying installation. Such an installation includes suitable drying 45 ovens, baking ovens or other chambers through which heated gas such as the products of combustion of the heaters, or air heated by the heaters, is forced or drawn by suitable power driven fans. Thus in Fig. 1 of the drawings there is 50 diagrammatically illustrated a multiple burner system adapted for use with such an industrial installation, there being a plurality of main burners 10 which in the present instance are arranged 55 in two groups 11 and 12.

With this arrangement the group 11 may be used to supply heat for one chamber of the system and the group 12 for another chamber. Thus the group 11 of main burners 10 is supplied with fuel from a supply pipe 13 which is controlled by a valve 14. The valve 14 is normally closed and has an actuator such as a solenoid 15 which opens the valve 14 when energized. The group 12 is fed from a similar supply pipe 16 under the control of a similar valve 17 and actuator 18.

5 The main burner 10 has a pilot burner 20 which is shown diagrammatically in Fig. 1, but which in actual practice is closely associated physically with respect to its related main burner 10. The pilot burners 20 are supplied with a 15 fuel such as gas from a common fuel line 21 under the control of a normally closed pilot fuel valve 22. An electrically operable actuator such as a solenoid 23 is operable to open the valve 22 when energized.

The pilot burners 20 are each provided with an electrical igniting device such as a spark plug 25, which spark plugs 25 are shown diagrammatically in Fig. 1, although in the actual installation each plug is mounted so that its spark points are located in the path of the pilot fuel as it discharges through the related pilot burner 20.

In the use of drying or baking installation of the type with which the present burner system is adapted to be employed, it is desirable that 30 the various chambers be purged of accumulated gases prior to the starting of the various burners; and it is also desirable that the draft creating means for the burners as well as the air or heat 35 circulating means be in operation before the burners are started.

To this end the opening of the various fuel valves is rendered dependent upon the proper 40 operation of the various draft or flow creating means. Thus the energizing circuit for the pilot fuel valve actuator 23 is such that it may be established only after a predetermined period of 45 operation of exhaust fan means for purging the gases from the various chambers of the system; while the energizing circuits for the actuators of the main fuel valve means are rendered dependent upon the energization of the pilot valve actuator.

As shown in Fig. 1, actuating power for the 50 various electrically operated elements of the system is taken from leads L₁ and L₂ which by means of a main switch 26 may be connected to leads L₃ and L₄ respectively. These leads L₃ and L₄ may include fuses 27, if desired. The lead L₄ constitutes the common power wire of the pres- 55

ent system and is connected to one terminal of the pilot gas valve actuator 23 by a wire 28, while the circuit from L₄ to the other terminals of the actuator 23 includes various safety switch means which insure proper operation of related elements of the installation prior to opening of the pilot gas valve 22.

Thus the present circuit from the line L₄ to the valve actuator 23 includes switch means 30 which is responsive to pressure in the gas main to make contact only if a predetermined gas pressure exists in the main. This switch means 30 has one terminal connected to lead L₄. This circuit also includes a pair of similar suction responsive switch devices 31 and 32 connected in series by wires 33 and 34 to the other terminal of the switch means 30. The two switch devices 31 and 32 are of the type having rockable flap members 31' which are responsive to air flow to close the associated switch. The switch device 31 is preferably mounted so as to be responsive to air flow created by the stack fan (not shown) of the system, while the switch 32 is preferably mounted so as to be responsive to air flow created by the exhaust fan (not shown) of the oven or other chamber which is to be purged of gases.

In the present system, the purging fans must operate for a predetermined time prior to the starting of the various burners, and to insure this delay, the circuit from the lead L₄ is associated with a time delay relay 35. The relay 35 has a time delay actuating circuit including a coil 36 one end of which is connected by a wire 37 to the other terminal of the switch device 32 while the other end of the coil 36 is connected by a wire 38 to lead L₄. After current flows through the time delay circuit for a predetermined time, a switch arm 39 of the relay is actuated to engage a contact 40 of the relay, the switch arm 39 being connected by a jumper wire 41 to the wire 37.

From the contact 40, a wire 42 extends to one terminal of a normally closed push button switch 43, the other terminal of which is connected by wires 44, 45 and 46, a normally open relay switch 47 and a wire 48 in series to the other terminal of the pilot valve actuator 23. The relay switch 47 is of the induction type having one coil 49 connected at one end to wire 45 and at its other end to lead L₄ by means of a wire 50. The other or control coil 52 of the relay switch 47 operates, when a circuit is closed through the coil 52, to cause the switch 47 to be closed, and this operation is manually induced by closure of a normally open push button switch 53. The contacts of this switch 53 are connected to opposite ends of the control coil 52 by wires 54, 55 and 56.

When the purging cycle has been completed so as to close the switch 39 of the time delay relay 35, the system is conditioned for starting of the pilot burners 20. This proper conditioning is visually indicated by an indicator light 58 connected between wire 45 and lead L₄. The pilot starting button 53 may then be depressed so as to energize the pilot valve actuator 23, and such energization is visually indicated by an indicator light 59 connected across the wires 28 and 48.

The starting button 53 is, in the present embodiment, maintained in its depressed position until the pilot burners 20 have been started so that a presence of the pilot flames may act on a series of safety detecting devices 60 to establish a holding circuit through the control coil 52 of the relay switch 47. As herein shown the detecting devices 60 are in the form of thermostatically actu-

ated switches each arranged to be closed by the heat from the pilot flame with which it is associated. The several detecting devices 60, therefore, are connected in series by wires 61, 62 and 63 across the ends of the coil 52. With this construction, the detecting devices 60 are associated one with each burner 20 so as to be subjected to the heat thereof, and hence the failure of one of the burners 20 during normal operation of the system will act to open the holding circuit through the coil 52. This permits opening of the switch 47 so as to cause shutting down all of the burners 20 and pilots 20 as will be hereinafter explained.

When the pilot starting button 53 is depressed so as to energize the pilot valve actuator 23, the spark plugs 25 of the several pilot burners 20 are also energized by high tension current so as to ignite the fuel gas fed to the pilot burners. In accordance with the present invention such energization of the spark plugs 25 is accomplished by means of an economical character which avoids duplication or excessive capacity in the various elements of the ignition system. Thus in the form herein shown the several spark plugs 25 are all energized from the secondary of a single transformer 65, of relatively small size and this is accomplished without undue load on the transformer. The primary of the transformer 65 is connected at one end to the line L₄ by a wire 66 while its other end is connected by wires 67, 68 and 69, a normally closed switch 70, and wires 71, 72 and 73 all in series to the wire 48. Thus when the pilot fuel valve 22 is opened, the transformer 65 is simultaneously energized.

In order that the single transformer 65 may serve to energize all of the spark plugs 25 without unduly loading the transformer, means is provided whereby the output potential from the secondary coil 65' is applied in rapid succession to the several spark plugs. This end is attained through the cooperation of a distributor device 75 which is shown in detail in Figs. 2 and 3 of the drawings. The distributor device 75 comprises a plurality of circumferentially spaced contacts 76 each connected by a wire 77 to the center terminal of one of the spark plugs 25. Centrally of the stationary contacts 76 a rotatable wiper arm 78 is mounted so as that in rotation of the arm 78 a circuit is made successively with each of the contacts 76. The central or rotatable wiper arm 78 is connected by a wire 79 to one end of the secondary coil 65' while the other end of the coil is grounded by a wire 80.

The rotatable arm 78 of the distributor device 75 is driven by an electric motor 81 which is energized simultaneously with the transformer 65 by wires 82 and 83 which connect the motor terminals to the lead L₄ and the wire 68 respectively.

In the form herein illustrated the distributor device 75 is mounted directly on one end of the motor 81, there being a connector housing 85 secured to the motor housing by screws 86 so as to surround the projecting end of the motor shaft 87. On the open face of the housing 85 a mounting plate 88 is fastened by screws 89, and an extension sleeve 90 connected to the shaft 87 as at 81 projects through a central bearing opening in the plate 88. The wiper arm 78 is mounted and keyed to the sleeve 90, and the several contacts 76 are mounted in an insulating cap 92 which houses the arm 78 and is secured to the plate 88 by screws 93. Each contact 76 is formed as a part of a connecting socket 94 so that suitably formed ends 95 of the wires 77 may be in-

serted into the sockets and thereby connected to the contacts. A similar connecting socket 86 is provided centrally of the cap 82 to receive the wire 79, this socket 86 having a stationary terminal 91 positioned centrally of the inner face of the cap 82 for constant engagement by a spring contact 98 carried on the wiper arm 78. On the end of the arm 78 and in circuit with the contact 98, a resilient wiper contact 100 is mounted

so as to cooperate with the contacts 76 successively as the arm 78 is rotated. With the distributor device 75 operating at motor speed, the output of the transformer 85 is applied to each spark plug 25 in rapidly reoccurring pulses so as to create a series of sparks or igniting arcs at each plug. The succession of arcs created at each plug is such as to ignite the pilot fuel with the same efficiency as if the current were applied continuously to each plug, and this result is economically attained by the use of but a single transformer.

As soon as the pilot burners 20 have been ignited, the system is in condition for starting of the main burners 10, and as hereinbefore pointed out, such starting of the main burners 10 is rendered dependent upon the proper energization of the several operative elements of the pilot burner starting means. Thus starting of the main burners 10 is attained through an energizing circuit which includes the wire 72, this wire being energized only when the pilot starting relay 47 has been actuated. To this end wires 101 and 102 extend in series from the wire 72 to one contact of a normally open switch 103. From the other terminal of the switch 103 wires 104 and 105 extend, and the main fuel valve actuators 15 and 18 are connected between wire 105 and lead L₃ so that when the switch 103 is closed, the main fuel valve actuators may be energized.

As herein shown the valve actuators 15 and 18 are on separate parallel circuits from the wire 105 and lead L₃, and each of these circuits preferably includes safety devices associated with the chambers heated by the burners.

Thus the lead L₃ is connected to one terminal of the actuator 18, while the other terminal is connected to the wire 105 by wires 106 and 107 which have safety devices 108 and 109 in series therewith. The safety device 108 preferably comprises a limit switch associated with the chamber heated by the group 12 of burners, while the safety device 109 comprises a flow switch similar to the switches 31 and 32 and sensitive to the flow of air created by the supply fans associated with said chamber. When the valve actuator 18 is energized, this condition is visually shown by an indicator light 110 connected between lead L₃ and the wire 106.

A similar parallel circuit to the valve actuator 15 is formed by a wire 111 from the lead L₃ to one terminal of the actuator and similar wires 106' and 107' safety devices 108' and 109' and a wire 112 in series from the other terminal of the actuator 15 to the wire 105. A similar indicator such as a light 110' is provided between the wires 111 and 106'.

The starting of the main burners 10 is preferably controlled manually, and to this end the switch 103 is provided as a part of a relay 115 which is actuated from its normal position of Fig. 1 under the control of a push button switch 116. As herein shown the relay 115 is of the induction type having a coil 117 connected by wires 118 and 119 between the wire 72 and the

lead L₃. A second or control coil 120 is provided in the relay 115, and when a circuit is completed through the coil 120 during energization of the coil 117, the relay is actuated. The coil 120 is therefore connected by wires 121 and 122 to the terminals of the push button switch 116, and a holding circuit for the coil 120 is provided by wires 123 and 124 from the wires 121 and 122 respectively to the contacts of a normally open switch 125. The switches 70, 103 and 125 all constitute parts of the relay 115 and are actuated thereby.

Since the switch 70 is rocked to its open position by actuation of the relay 115, the circuits to the transformer and to the motor 81 are broken and the operation of the electric ignition is thereby terminated automatically when the main burners 10 are started.

The relay switch 45, of course, constitutes the primary safety relay of the present multiple burner system, and when a flame or heat failure in any of the pilot burners is detected by the associated detector 60 the holding circuit of the relay switch 46 is broken and the switch returns to its normal open position so as to cut off the energizing circuits of both the main and pilot burner valve actuators. These valves then return to their normal closed position and the operation of all the burners is stopped.

Since the single main safety control relay 47 governs the energization of the pair of wires L₃ and 105, and since the main burners 10 are arranged singly or in pairs in parallel circuits from these wires L₃ and 105, it will be evident that the present system provides for controlling a plurality of main burner units without the usual duplication of equipment. Thus it will be clear that each burner 10 would, in accordance with the present invention, be disposed in a separate parallel circuit such as that formed between the wires 111 and 112; or that a larger number of groups such as the groups 11 and 12 of main burners could be similarly controlled from the control wires L₃ and 105. Hence the single starting mechanism which insures proper sequence of the various operations involved in the starting of the burners may serve to control a large number of main burner units. The present arrangement is particularly flexible in use for the reason that all of the burners 10 need not be set in operation unless such operation is desirable. Thus, if the user wishes to employ only the burners of group 12, it is only necessary to turn off the blowers or fans which cause closure of the safety control device 109. By this action the circuit to the fuel valve actuator 18 is broken, with the result that fuel to the burners of the group 12 is shut off. In such a case, the pilots associated with this group would continue to burn so as to insure ignition of the main fuel upon reclosure of the switch 109.

I claim:

1. In a burner system having a plurality of pilot burners and main burners, individual spark plugs for igniting said pilot burners, means for supplying fuel to said pilot burners including an electrically actuated control valve and an energizing circuit for said valve, means for supplying high potential to said spark plugs including a distributor and a driving motor therefor, said distributor being operable to energize said plugs in rapid succession when driven by said motor, a common control means for controlling the motor and said valve energizing circuit, means for supplying fuel to said main burners including at least

one electrically actuated valve and an energizing circuit therefor, and other common control means operable to control the energizing circuit for the main burner fuel supply means and to control said motor.

5. 2. In a burner system having a plurality of pilot burners and main burners, individual spark plugs for igniting said pilot burners, means for supplying fuel to said pilot burners including an 10 electrically actuated control valve and an energizing circuit for said valve, means for supplying high potential to said spark plugs including a high tension current source, a distributor and a driving motor therefor, said distributor being operable to energize said plugs in rapid succession when driven by said motor, a common control means for controlling the motor, said high tension current source and said valve energizing circuit, means for supplying fuel to said main 20 burners including at least one electrically actuated valve and an energizing circuit therefor, and other common control means operable to control the energizing circuit for the main burner fuel supply means and to control said motor and said 25 high tension source.

3. In a multiple burner system having a plurality of main burners and a plurality of pilot burners therefor, means operable to start said pilot burners including fuel supply valve means and 30 electrical ignition means therefor, said ignition means including spark plugs for the individual pilot burners, a transformer and a motor driven distributor operable to apply the output of said transformer to said plurality of spark plugs in 35 rapid succession, said motor and said transformer being energized by said pilot burner starting means concurrently with the operation of the pilot fuel supply valve means, means for starting said main burners including fuel supply 40 means, and means operable as an incident to the operation of said main burner starting means to deenergize said electrical ignition means.

4. In a multiple burner system having a plurality of main burners and a plurality of pilot burners therefor, means operable to start said pilot burners including fuel supply valve means and electrical ignition means therefor, said ignition means including ignition devices for each of the individual pilot burners, a transformer and a motor driven distributor operable to apply the output of said transformer to said individual ignition devices in rapid succession, said motor and said transformer being energized by said pilot burner starting means concurrently with the operation 55 of the pilot fuel supply valve means, means for starting said main burners including fuel supply means, and means operable as an incident to the operation of said main burner starting means to deenergize said electrical ignition means.

60 5. In a multiple burner system having a plurality of main burners and a plurality of pilot burners therefor, means to start said main burners including fuel supply means and control valve means therefor, means operable to start said pilot burners including fuel supply means and electrical ignition means therefor and common starting means for said fuel supply means and said electrical ignition means, said ignition means including individual ignition devices for the individual 65 pilot burners, and a source of current and a motor driven distributor operable to apply current from said source to said individual ignition devices in rapid succession, said motor and said source being primarily controlled by said pilot burner starting means and secondarily controlled by said

main burner starting means to deenergize said electrical ignition means when said main burners are started.

6. In a multiple fuel burner system having a plurality of main burners and a plurality of pilot 5 burners, fuel supply means for said main burners including normally closed main valve means and electrical actuating means operable when energized to open said main valve means, fuel supply means for said pilot burners including normally closed pilot valve means and electrical actuating means operable when energized to open said pilot valve means, electric ignition means for initiating combustion of the pilot fuel including a plurality of spark plugs associated one with each pilot 15 burner, a transformer and a motor driven distributor operable to apply the output of transformer to said spark plugs in rapid succession, a common energizing circuit for said pilot valve actuating means, said motor and said transformer including 20 a first manually controlled circuit closing means, and means for energizing said main valve actuating means comprising a main valve circuit primarily controlled by said first manual circuit closing means and secondarily controlled by a second 25 manually controlled circuit closing means, said second circuit closing means being operable when said main valve circuit is closed to open the circuit to said motor and said transformer.

7. In a multiple fuel burner system having a plurality of main burners and a plurality of pilot burners, fuel supply means for said main burners including normally closed main valve means and electrical actuating means operable when energized to open said main valve means, fuel supply means for said pilot burners including normally closed pilot valve means and electrical actuating means operable when energized to open said pilot valve means, electric ignition means for initiating combustion of the pilot fuel including a plurality of ignition devices associated one with each pilot burner, a source of ignition current and a motor driven distributor operable to apply current from said source to said ignition devices in rapid succession, circuit means for energizing said pilot valve actuating means and said motor and for controlling said source including a first manually controlled circuit closing means, means for energizing said main valve actuating means comprising a main valve circuit primarily 45 controlled by said first manual circuit closing means and secondarily controlled by a second manually controlled circuit closing means, said second circuit closing means being operable when said main valve circuit is closed to open the circuit to said motor and said transformer and having a holding circuit governed and completed only during continued closure of said first circuit closing means, a plurality of detecting devices associated one with each of said pilot burners, and a holding circuit for maintaining said first circuit closing means in its circuit closing relation and governed jointly by said plurality of detecting devices.

8. In a multiple fuel burner system having a 65 plurality of main burners and a plurality of associated pilot burners, fuel supply means for said main burners, fuel supply means for said pilot burners, means for igniting said pilot burners including electric ignition means for initiating 70 combustion of the pilot fuel having a plurality of individual electric igniting devices associated one with each pilot burner, a transformer, a motor driven distributor operable to apply the output of transformer to said igniting devices in rapid 75

succession, means for starting said pilot burners including a control for energizing said motor and said transformer and for operating said pilot fuel supply means, and means for starting said 5 main burners primarily controlled by said pilot burner starting means and operable upon said control when said main burners are started to stop said motor and deenergize said transformer.

9. In a multiple fuel burner having a plurality 10 of main burners, and a plurality of associated pilot burners, a plurality of parallel control circuits each operable to govern the operation of one or more of said main burners, each of said parallel circuits including one or more safety

switch devices responsive to operating conditions of the main burner controlled by its circuit, a common safety switch means, governing means for said common safety switch means including safety devices responsive to the operating conditions of each of said pilot burners and operable to actuate said common safety switch means to one relation when all of said pilot burners are operating and to another relation when any one of said pilot burners is inoperative, and a safety 10 circuit governed by said common safety switch and connected to all of said parallel control circuits in governing relation thereto.

RALPH J. PLEIN.
